CLAIM

The ornamental design for a wireless earbuds with charging case, as shown and described.

DESCRIPTION

FIG. 1 is a front, right and top perspective view of a charging case of the wireless earbuds with charging case showing my new design where the charging case is in a closed state;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the wireless earbuds with charging case, shown in use with the wireless earbuds received in the charging case;

FIG. 9 is a front, right and bottom perspective view of wireless earbuds of wireless earbuds with charging case, shown separately for ease of illustration;

FIG. 10 is a top, rear and left perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines in the figures illustrate portions of the wireless earbuds with charging case that form no part of the claimed design.
